COMBINATION TABLE AND BENCH CONSTRUCTION

Filed July 11, 1942

Inventor:
Joseph C. Higgins.
By: W. F. Kellogg Atty.

underside of the table top 2, thus securing the same to said top, while the flattened apertured portions 8 and 11 of their respective body formations are arranged in opposed contacting relationship.

In order that the end supporting frames 1 will be rigidly braced with respect to each other, a longitudinally disposed tubular bracing element 13, of a length substantially corresponding to the length of the table top 2, is provided. The opposite ends of this bracing element 13 are formed with apertured and flattened outwardly extending fingers 13' arranged in juxtaposed relation to the relatively overlying apertured portions 8 of the oblique sides 5 of the legs 4 and the braces or struts 9. Bolts or like fastening devices 14 are engaged through these overlying and juxtaposed apertured portions 8 and 11 and fingers 13'. Hence, a fixed and rigid connection will be effected between the end supporting frames 1 and the longitudinal bracing element 13.

To effect further rigidifying or bracing of the table construction, I may and preferably do provide a plurality of relatively opposed diagonally extending tubular bracing members 15, each of which have flattened apertured and angularly disposed fingers 15' provided upon their opposite ends. The upper ends of the bracing elements 15 are secured to portions of the underside of the table top 2 by engaging bolts or the like 16 through their adjacent apertured fingers 15' and with said top, as illustrated in Figure 1. The remaining ends of the outermost of said bracing members 15 are preferably connected by the aforesaid connecting bolts 14 to the adjacent apertured portions 8 and 11 of the oblique sides 5 of the legs 4 and the bracing elements 9, while the lower and juxtaposed ends of the remaining bracing members 15 are fixedly connected to an intermediate portion of the longitudinal element 13 by passing a bolt 17 therethrough.

A transversely disposed horizontal supporting bracket 18 is arranged over the longitudinal element 13, and as shown in the Figures 1 and 2 of the accompanying drawing, is fixedly connected thereto by engaging the aforesaid connecting bolt 17 therethrough. Resilient bumper blocks 19, made of rubber or other suitable material, are fixedly carried upon the upper side of the bracket 18 at its opposite extremities and serve a purpose which will be hereinafter described.

The benches 3 each consist of relatively spaced supporting frames 20, preferably made from material corresponding to that of the table end supporting frames 1. Said frames 20 are bent or formed to provide substantially triangular bodies, as shown in Figure 2 of the drawing, including vertical outer sides or uprights, feet or surface engaging basal portions 21 and outwardly bowed substantially V-shaped inner side portions 22, the extremities or medial bends of which are adapted to be pivotally connected to appropriate portions of the legs 4 of the table supporting frames 1, as hereinafter more fully described. Bench tops or seats 23, of lengths substantially corresponding to the length of the table top 2, are provided the thus paired bench supporting frames 20 and are fixedly connected thereto by engaging bolts or similar fastening devices 24 through flattened and angularly disposed apertured fingers 20' on the upper extremities of the vertical portion and portion 22 of frame 20 with adjacent portions of the underside of the bench tops 23. Bracing members 25, consisting of lengths of tubular metal, are obliquely and longi-

tudinally disposed between the basal portions of each of the supporting frames 20 and the adjacent end portions of the top of the bench top or seat 23 being connected to such portions of the frames 20 and the top 23 by bolts or like fastening devices 26 passing through apertured angular fingers on the opposite ends of the same into fixed engagement with said frames and top 23. Additional supporting legs 27 may be and preferably are provided the intermediate portions of each of the benches 3 and, as will be observed upon reference to Figure 1 of the accompanying drawing, consist of substantially V-shaped tubular metal pieces of suitable heights or lengths, the free ends of which are formed with apertured and angularly disposed bracket fingers 28 contacted with adjacent portions of the underside of the bench top 23 and fixedly connected thereto by passing bolts or like fastening devices 29 through the same into engagement with adjacent portions of said bench top or seat 23. As will be understood, the lengths or heights of these supporting legs 27 correspond to the heights or lengths of the bench supporting frames 20 for an obvious purpose.

As hereinbefore stated, the inner or substantially V-shaped inner sides of the bench supporting frames 20 are pivotally connected to the outer sides of the legs of each of the table supporting frames 1. To accomplish such connection, openings are formed in appropriate portions of the outer sides of said legs 4 and in the angled portions or bends of the bowed or substantially V-shaped sides 22 of the bench supporting frames. Spacer sleeves 30 and 30' are engaged through these respective openings, whereupon connecting bolts 31 are longitudinally passed through the sleeves and locked in relation thereto by means of nuts 32 turned on to their screw threaded shank portions, as illustrated in Figure 3 of the accompanying drawing. By reason of this specific form of connection, it will be understood that substantially free pivotal movement of the bench supporting frames 20 with respect to the table supporting frames 1 will be permitted and, at the same time, that a maximum of firmness or stability will be afforded the pivotal connection.

Due to the fact that the supporting frames 20 of the several benches 3 are pivotally connected to the table supporting frames 1 in proximity to their respective lower portions, it will be observed that when either or both said benches are swung to their inoperative or nested positions between the table frames, as shown in Figure 2, the inner marginal edge of the top or seat 23 of such bench or benches will be brought to rest upon & engage with the particularly adjacent bumper block 19 provided on the horizontal bracket 18; moreover, by reason of such specific location of the pivotal connection between the bench supporting frames and the table supporting frames, the now outward portion or portions of said bench or benches will be over-balanced and in consequence, will be prevented from undesirably moving or dropping outwardly and downwardly to operative positions. It will be also understood and appreciated that when the table benches 3 have been moved or swung to their respective inoperative or out-of-the-way positions under the table top 2 and within its frame, a material conservation of space will be effected and too, greater table by-passing convenience will be afforded.

Obviously, when the table benches 3 have been moved or swung to their operative positions and 75 are occupied or loaded, definite stabilizing of the

table will be thereby effected and in consequence, undesirable shifting, tilting or even overturning of the thus stabilized or more firmly anchored table will be prevented. By the same token, it will be understood that an even and uniform distribution of those stresses applied to both the table top 2 and the bench tops 23 will be effected throughout their respective supporting frames; also, that the formation of the basal or feet portions of both the table frames and the bench frames is such that they will provide a minimum of contacting area with a receiving and supporting surface, i. e., a floor or the like, hence, reducing wear and tear upon the latter to a material extent.

Manifestly, the construction shown is capable of further modification, and such modification as is within the scope of my claims, I consider within the spirit of my invention.

I claim:

1. A table, including end frames and a top, benches substantially parallel to the opposite sides of said top, each comprising end supporting frames and a top of a length less than the distance between the end frames, each said end supporting frames having their inner sides substantially V-shaped with the angular extremities thereof extended beyond the adjacent sides of their respective tops, means pivotally inter-connecting said angular extremities with adjacent portions of the corresponding sides of said end frames, and other means on the table for receiving said benches, at times, and supporting them in substantially horizontal positions beneath the table top.

2. A table, including end frames and a top, benches substantially parallel to the opposite sides of said top each comprising end supporting frames and a top of a length less than the distance between the end frames, the normally inner sides of each said end supporting frames being substantially V-shaped with the angular extremities outermost and disposed below their respective horizontal medial portions, means pivotally inter-connecting said end frames and end supporting frames adjacent said angular extremities of the inner sides of the end supporting frames and adjacent portions of said end frames, and means on the table beneath its top for receiving said benches, at times, and supporting them in substantially horizontal planes beneath the table top.

3. A table, including end frames and a top,

benches in proximity to the opposite sides of the end frames, each comprising supporting frames and a top of a length less than the distance between the end frames, portions of the normally inner sides of the supporting frames being outwardly bowed, and the outermost extremities of said bowed portions being arranged below the horizontal medial portions of said frames and disposed outwardly and beyond the bench top, 5 means engaging the outermost extremities of said bowed portions pivotally connecting the same to portions of the end frame sides, and means on the table beneath its top engageable by the benches, at times, for supporting said benches in 10 positions beneath the table top at substantially right angles to their normal positions.

4. A table, including end frames and a top, each end frame comprising relatively opposed legs, the lower portions of said legs being inwardly 20 disposed and upwardly bent, a longitudinal bracing member beneath the table top connected to the upwardly bent and inwardly disposed portions of said legs, benches of lengths less than the distance between said end frames substantially 25 parallel to the opposite sides of said top, means pivotally connecting portions of said benches to portions of said end frames at points below the horizontal medial portions of said benches, and means on said longitudinal bracing member engageable by the benches, at times, for supporting said benches in positions beneath the table top at substantially right angles to their normal positions.

5. A table, including end frames and a top, 30 bracing means beneath the top connected to portions of the end frames between the opposite sides thereof, benches in proximity to the opposite sides of the end frames each comprising substantially U-shaped supporting frames and a top of a length less than the distance between said end frames, portions of the normally inner sides of the U-shaped supporting frames being disposed outwardly of and beyond their respective tops and 40 pivotally connected to adjacent portions of the opposite sides of the end frames, and means on said bracing means below the table top engageable by the benches, at times, for supporting said benches in positions beneath the table top at substantially right angles to their normal positions.

JOSEPH C. HIGGINS.
